UNITED STATES PATENT OFFICE.

ALLEN T. WILLIAMS, OF BOSTON, MASSACHUSETTS.

PICTURE-HOOK.

1,103,721.

Specification of Letters Patent. Patented July 14, 1914.

Application filed August 21, 1913. Serial No. 786,017.

To all whom it may concern:

Be it known that I, ALLEN T. WILLIAMS, a citizen of the United States, residing at Boston, in the county of Suffolk and State 5 of Massachusetts, have invented certain new and useful Improvements in Picture-Hooks; and I do hereby declare the following to be a full, clear, and exact description of the invention, such as will enable others skilled 10 in the art to which it appertains to make and use the same.

This invention relates to new and useful improvements in picture hooks and has for its object to provide a hook which may be 15 readily attached to the usual picture molding and still remain substantially immovable thereon until it is desired to remove the same.

Considerable difficulty has been experienced in the use of picture hooks in connection with molding, inasmuch as the hooks were apt to become displaced and fall from their position when it is desired to hang a picture thereon and my invention has for 25 its object to eliminate the disadvantage mentioned and by means of a suitable mechanism the hook is held securely in its position on the molding and accidental dislodgment of the same is substantially eliminated. 30

Another object of my invention is to provide a simple device which may be easily operated and cheap to manufacture.

With the above and other objects in view 35 I now proceed to describe my invention in the following specification and accompanying drawings, in which—

Figure 1 is a view of a fragment of picture molding showing my improved hook 40 applied thereto, and Fig. 2 is a transverse sectional view taken on line 2—2 of Fig. 1.

Referring to the drawings by characters of reference, 5 indicates generally the usual picture molding comprising the head 6 and 45 the base portion 7. This head 6 is spaced from the wall as clearly illustrated in Fig. 2 and the hook is adapted to pass partly there around and be held in position thereon.

50 My improved picture hook comprises the usual body portion 8 having formed at the upper end thereof the hook member 9 which is adapted to engage the head 6 of the picture molding and hold the body portion in place. At the lower extremity of the body

portion is the usual wire retaining hook 10 over which the usual picture hanging wire is adapted to pass.

A resilient wire 11 is secured to the hook 9, as clearly illustrated at 12, and terminates 60 at its opposite extremity in the point 13, which is adapted to enter the picture molding and hold the device in place. Intermediate the point of the portion 11 I preferably provide the outwardly curved portion 65 14, which is adapted to receive the loop 15 formed on the knob 16, as clearly shown in Fig. 2.

In use my improved picture hook is placed in position on the molding in the usual manner. The knob 16 is then pulled outwardly which will cause the point 13 to spring out and the hook may be placed at the desired point on the molding. Upon releasing the knob 16 it will be obvious that 75 the point 13 will be pressed into the soft wood of the picture molding and in that way prevent accidental displacement of the hook with relation to the molding. When it is desired to release the hook from its position 80 the only operation necessary is the pulling of the knob 16 which will cause the point 13 to come out of engagement with the molding as the hook may be removed without further trouble.

85 While in the foregoing I have shown and described the preferred embodiment of my invention, I wish it to be understood that I may change the specific arrangements of parts without in any way departing from 90 the spirit and scope of my invention.

What I claim is:—

1. The combination with a picture hook of resilient wire secured at one end to one end of said hook and curved to lie flat upon the 95 outer face of said hook, an angularly and inwardly extending pointed portion extending through an aperture in the hook to engage the picture molding and being formed integral with the wire, and a knob loosely connected with the wire at the point of formation thereof with the pointed angularly extended portion.

2. The combination with a picture hook having a molding hook at one end and a 105 picture wire supporting hook at the other end of a resilient wire permanently secured at one end adjacent to the free end of the molding hook and being bent to lie upon the outer face of the picture hook, an angular 110

and inwardly extended pointed extension formed on the free end of the wire and extending through an aperture in the picture hook to engage the molding, said wire being bowed outwardly at the point of its formation with the extension and a knob loosely connected with the bowed portion.

In testimony whereof I affix my signature in presence of two witnesses:

ALLEN T. WILLIAMS.
